UNITED STATES PATENT OFFICE.

WILLIAM GIFFORD JONES, OF EVANSTON, ILLINOIS, ASSIGNOR TO ACCOUNTING DEVICES COMPANY, OF EVANSTON, ILLINOIS, A CORPORATION OF ILLINOIS.

LOOSE-LEAF BINDER.

1,241,220.

Specification of Letters Patent. Patented Sept. 25, 1917.

Application filed August 28, 1916. Serial No. 117,350.

To all whom it may concern:

Be it known that I, WILLIAM GIFFORD JONES, a citizen of the United States, residing at Evanston, in the county of Cook and 5 State of Illinois, have invented a new and useful Improvement in Loose-Leaf Binders, of which the following is a specification.

This invention relates particularly to loose-leaf binders having clamping-members joined by flexible connections, or flexible binding-posts; and the primary object of the invention is to provide simple and durable extension means for the flexible binding-posts, whereby the binding-posts can be 15 lengthened at will, without disturbing the connections with the clamping-members of the binder.

The invention is illustrated in its preferred embodiment in the accompanying 20 drawing, in which—

Figure 1 represents a broken longitudinal sectional view of the clamping-members of a loose-leaf binder, showing the take-up mechanisms and the improved flexible post- 25 connection between the clamping-members; Fig. 2, a broken sectional view taken as indicated at line 2 of Fig. 1; Fig. 3, an enlarged broken sectional view of the improved flexible post employed; and Fig. 4, details of 30 the extension members with which the flexible post is equipped at an intermediate point, whereby the post can be lengthened at will without disturbing the connections between the ends of the post and the clamping-members.

In the construction illustrated, A, A' represent the clamping-members of a loose-leaf binder, such as a current ledger or transfer binder; B, B' represent the take-up 40 mechanisms with which the clamping-members are equipped; and C represents an improved flexible connection, or flexible binding-post, connecting the clamping-members.

In the illustration given, each of the 45 clamping-members of the binder is of hollow or flattened tubular form and equipped interiorly with take-up mechanism. The take-up mechanism, in the form illustrated, comprises, in each case, a right-and-left threaded screw-rod 1 which is journaled in the ends of the tubular clamping-members, and nuts or followers 2 within the tubular clamping-members and working on the screw-rods. It will be understood that ordinarily each screw-rod is equipped with a

pair of nuts, one working on each end-portion of the screw-rod, and that a pair of flexible binder-posts are employed. The screw-rod is provided with a squared end 3 adapted to receive a key or actuating-crank 60 by means of which the screw-rod may be actuated.

The flexible post C is preferably a chain-post, comprising series of connected similar links 4 and special links 4^a and 4^b; a swiveled post-section 4^c; and any desired number of insert post-sections 4^d.

The chain-post C is preferably of circular cross-section. The links 4 are short and are close-connected by means of small, flat links 5 in the manner disclosed in my Patent No. 1,184,349, granted May 23, 1916. The special link 4^a is connected by a similar flat link 5 to the adjacent link 4. The special link 4^b is shown provided with an extension ear or 75 eye 6 by means of which it is connected with the adjacent link 4.

The special link 4^a is provided at one end with a threaded socket 7; and the special link 4^b is provided with a bore or socket 8. 80 The post-section 4^c is provided at one end with a reduced extension 9 which is swiveled in the bore 8 of the link 4^b, being rotatably secured therein by means of a pin 9^a which engages a circumferential groove 9^b with 85 which the extension 9 is provided. The post-section 4^c is equipped at its opposite end with a reduced threaded extension 10, which is adapted to screw into the threaded socket 7 of the special link 4^a. 90

The insert post-section 4^d is provided at one end with an internally threaded socket 11, and at the opposite end with a reduced threaded extension 12.

In the illustration given, the insert post-section 4^d has the portion 12 screwed into the threaded socket 7 of the special link 4^a; and the reduced threaded extension 10 of the swiveled post-section 4^c is screwed into the socket 11 of the insert post-section 4^d. Any 100 desired number of insert post-sections 4^d may be interposed between the special link 4^a and the post-section 4^c, which has swiveled connection with the special link 4^b.

The link portions of the flexible post pass 105 about curved bearings 13 with which the clamping-members are provided, and extend into the clamping-members, the extremities of the flexible post being firmly secured to the nuts 2.

From the description given, it will be understood that the improved flexible post is provided at an intermediate point with means for receiving extension inserts, whereby the flexible post may be lengthened at will without disturbing the connections between the extremities of the flexible post and the clamping-members. In the illustration given, both extremities of the flexible post are connected with the take-up mechanisms of the clamping-members. This is the preferred arrangement, but in any case it is desirable to avoid disturbing the connections between the flexible post and the clamping-members. This object is accomplished in a simple and effective manner by the invention herein described, without interfering in any manner with the strength and durability of the flexible binding-posts and their connections, which are called upon to sustain heavy strain in the use of the binder.

The foregoing detailed description has been given for clearness of understanding only, and no unnecessary limitation should be understood therefrom, but the appended claims should be construed as broadly as permissible in view of the prior art.

What I claim as new and desire to secure by Letters Patent is—

30 1. In a binder, the combination with clamping-members equipped with take-up mechanisms, of a flexible post connected at its extremities with said take-up mechanisms and provided at an intermediate point with 35 an extension insert, whereby said post may be lengthened at will without detachment from said take-up mechanisms.

40 2. In a binder, the combination with clamping-members, at least one of which is provided with take-up mechanism, of a chain-post connecting said clamping-members and having an extremity connected with said take-up mechanism, said chain-post provided at an intermediate point with links 45 adapted to receive post-inserts, whereby said post may be lengthened without disturbing the connections at the extremities.

50 3. In a binder, the combination with clamping-members, at least one of which is provided with take-up mechanism, of a chain-post connecting said clamping-mem-

bers and having an extremity connected with said take-up mechanism, said chain-post provided at an intermediate point with links having socket-connections, whereby insert post-sections may be interposed to enable the chain-post to be lengthened without disturbing the connections with the clamping-members.

4. In a binder, the combination with 60 clamping-members, at least one of which is provided with take-up mechanism, of a chain-post connecting said clamping-members and having an extremity connected with said take-up mechanism, said chain-post 65 having a link equipped with a swiveled post-section and having another link adapted for connection either with said swiveled post-section or an insert post-section.

5. In a binder, the combination with 70 clamping-members equipped with take-up mechanisms, of a chain-post connected at its extremities with said take-up mechanisms, said chain-post having a link equipped with a swiveled post-section and another link provided with a socket, and an insert post-section 75 between said swiveled post-section and said last-named link.

6. In a binder, the combination with 80 clamping-members equipped with take-up mechanisms, of a flexible post connected at its extremities with said take-up mechanisms and provided at an intermediate point with socket connections for receiving insert post-sections, and insert post-sections whereby 85 said flexible post may be lengthened without disturbing the connections with the take-up mechanisms of the clamping-members.

7. In a binder, the combination with 90 clamping-members, at least one of which is provided with take-up mechanism, of a chain-post connecting said clamping-members and having an extremity connected with said take-up mechanism, said chain-post having an intermediate link provided with a 95 swiveled member and socket-connections between said swiveled member and an adjacent link, whereby insert post-sections may be interposed to enable the chain-post to be lengthened without disturbing the connections with the clamping-members.

WILLIAM GIFFORD JONES.
